LIQUID FLOW INDICATOR

Lena M. Rugel and Paul F. Rugel, Dallas, Tex.

Application July 11, 1935, Serial No. 30,862

1 Claim. (Cl. 116—117)

This invention relates to liquid flow indicators and it has particular reference to an attachment for the discharge line of a gasoline pump or the like for visibly indicating the flow of liquid therefrom.

The principal object of the invention is to provide a housing having sides of transparent material and in which is provided a rotary member actuated by liquid. The invention further provides for the attachment of the housing to the outlet passage of a dispensing pump for gasoline or the like in order that a purchaser may observe the movement of the rotary member, indicating to him that his purchase is actually being delivered into his fuel tank or other receptacle.

Another object of the invention is to provide a device of the character specified which is mounted exteriorly of the pump and for this reason, dismantling of the pump is not required nor is it necessary to alter any feature thereof to install the invention.

With the foregoing objects as paramount, the invention has particular reference to its salient features of construction and arrangement of parts to become manifest as the description proceeds, taken in connection with the accompanying drawing, wherein:—

Figure 1 is an elevational view of a device constructed according to the present invention with portions broken away.

Figure 2 is a vertical section on lines 2—2 in Figure 1.

Figure 3 is a detailed view of a conventional type of gasoline pump, showing one of the applications of the invention, and

Figure 4 is a modified form of the invention shown in Figure 1.

Continuing with a more detailed description of the drawing, 1 designates the fluid or liquid outlet of the gasoline pump 2, into which is threaded a nipple 3 which is received by one end of the liquid passage 4 of the invention.

It is preferred that the invention be constructed out of a single casting composed of any suitable material and this casting embodies a circular housing 5, the edges of which are shouldered as shown in Figure 2 on either side, to receive glass covers 6. The covers 6 are held in place by the bezels or rings 7, the latter in turn being secured by screws 8. A suitable sealing medium 9 is interposed between the annular shoulders of the housing and the glass 6 on one side and the bezel 7 and the glass 6 on the other side of the latter. The sealing medium prevents escape of the liquid at the joints and for all practical pur-

poses litharge and glycerin may serve as the sealing medium.

Formed integral with the housing 5 and dependent to a point immediately below the center thereof is a bracket 10, having lateral braces 11. This bracket serves as a support for the pivot 12 of the rotary element 13. In the present case this element is comprised of a casting having a plurality of relatively spaced vanes 14 formed integrally with its outer periphery so that they will successively pass through the liquid passage 4 as apparent in Figure 1. The curvature of these vanes is such that maximum rotation may be imparted to the rotary element 13 by the liquid flowing through the passage 4 as it is transferred from the pump 2 through the said passage 4 and hose 15 to the fuel tank of an automobile.

The peculiar construction of the rotary element 13 allows for an annular cavity between the vanes 14 and the axis of the said element. The periphery of the cavity is provided with a series of semi-circular recesses 16 and in one of these recesses rests a ball 17 which cannot escape from the cavity.

Obviously, the fluid in passing as explained above imparts rotation to the rotary element 13, visibly indicating flow of the liquid and displacing the ball 17, which latter cannot come to rest in any of the recesses until the rotary element ceases to rotate. As an advertising attraction or otherwise, one of the recesses 16 is identified at 18 with a definite mark.

In Figure 4 is shown a modified example of the invention, differing only in that instead of providing the annular recesses and the corresponding ball 17, an arrow or pointer 19 is provided in fixed relation to the rotary element 20 which is actuated by the liquid passing through the passage 21. A suitable advertisement may be placed at 22 in Figure 4.

Manifestly, the construction shown is capable of considerable modification and such modification as is considered within the scope and meaning of the appended claim is also considered within the spirit and intent of the invention.

What is claimed is:

In a liquid flow indicating device, the combination comprising a liquid passage, a circular housing having transparent sides, arranged to be interposed between the point of liquid supply and the point of discharge and having communication with said passage, a wheel whose rotary axis is offset relative to said passage and having spaced, arcuate vanes on its periphery in spaced relationship and rotatably disposed in said hous-

ing whereby said vanes will successively enter said passage to be actuated by the liquid conveyed through said passage to visibly indicate the flow of liquid from the supply, an annular flange 5 from which said vanes extend, having in its inner periphery a multiplicity of successive depressions,

and a spherical element arranged to be received in one of said depressions upon cessation of rotation of said wheel.
